BREATHING ASSISTOR VALVE

John H. Emerson, Arlington, Mass.

Application March 28, 1952, Serial No. 279,105

5 Claims. (Cl. 128—203)

This invention relates to valves and more particularly to a valve of the demand type customarily interposed between a source of compressed gas, as for example oxygen, and a device from and into which a patient breathes, as for example a face mask, anesthesia bag or the like, for assisting the patient to breathe under conditions where the patient by himself is capable of initiating inhalation but is incapable of completing adequate depth of inhalation. It also may be used to assist a patient who is able to breathe but is in such condition that the exertion required for breathing is undesirable and should be reduced.

One object of the invention is to provide a novel breathing assistor valve of the character described which upon the patient's initiation of inhalation will assure the enforced delivery of life sustaining gas at a predetermined pressure and in predetermined volume to fill the patient's lungs without requiring any further effort on the patient's part and without injury to his lungs and which when the period of artificial inhalation has terminated will permit normal exhalation by the patient.

Another object of the invention is to provide a valve of the character described which makes possible the maximum utilization of gas received from the source of compressed gas during the inhalation period not only to control the volume of gas so received but to increase such volume through the addition of a less expensive gas such as air during enforced delivery, thereby to effect a substantial economy in the use of the compressed gas heretofore unattained in prior art devices.

Another object of the invention is to provide a valve of the character described which provides an additional supply of gas under pressure simultaneously with and only during the period of artificial inhalation for operating auxiliary equipment, as for example, an atomizer for administering medicine to the patient.

Other objects of the invention are to provide a valve of the character described which is simple, compact and durable in construction, dependable in use, easy to disassemble, clean and re-assemble and economical to manufacture.

Other and further objects and advantages of the invention will be pointed out in the following more detailed description and by reference to the accompanying drawings wherein

Fig. 1 is a front elevation of one embodiment of the invention;

Fig. 2 is a rear elevation of the embodiment of Fig. 1;

Fig. 3 is a side elevation of the embodiment of Fig. 1;

Fig. 4 is the section along the line 4—4 of Fig. 1;

Fig. 4a is a view similar to that of Fig. 4 with the upper portion broken away, except that a second inhalation valve 68 is substituted for exhalation valve 80, the escape of gas during exhalation being provided by exhalation valve 129 (see Figs. 6 and 7);

Fig. 5 is an enlarged longitudinal section along the line 5—5 of Fig. 1;

Fig. 6 is a front elevation showing the manner in which

2

the valve of the invention is used with a face mask, the tube connecting the valve with the face mask being broken away;

Fig. 7 is a top view showing the manner in which the valve of the invention is used with a face mask and atomizer;

Fig. 8 is an enlarged section along the line 8—8 of Fig. 7;

Fig. 9 is a front elevation showing the manner in which the valve of the invention may be used for the administration of anesthesia, the tube connecting the valve with the casing enclosing the anesthesia bag being broken away; and

Fig. 10 is a further enlarged partial section along the line 5—5 of Fig. 1 showing the needle valve and associated passages and parts.

Referring to Figs. 1—5 of the drawings, the valve comprises a housing 1 made of aluminum or other suitable material, comprising a narrow elongate body portion 2 and an enlarged annular substantially dish-shaped body portion 3, the elongate body portion 2 having a reduced gas receiving end 4 and a delivery end 5. A cover 6, preferably formed of the same material as the housing and formed substantially in the shape of an inverted dish 20 cooperates with the body portion 3 to form a chamber 7 which receives a flexible diaphragm 8 dividing the chamber into the atmospheric pressure chamber 9 and the control chamber 10.

Within the housing, the portion of the elongate body portion 2 adjacent to the body portion 3 is formed with an elongate channel 11 extending longitudinally of the body portion 2 and constituting a part of the control chamber 10 and having a floor 12 and end walls 13 and 14. The cover 6 and body portion 3 are formed with peripheral flanges 16 and 17 provided respectively with an annular recess 18 and 19 and are secured together at said flanges by suitable means here shown for example as screws 20. The peripheral margin of the diaphragm is received and clamped between said flanges and is provided with annular spaced openings to receive the screws 20, whereby the portion of the diaphragm inwardly of its peripheral margin is afforded ample room to move inwardly and outwardly within the control chamber 10. The cover 6 is provided with a screened port 23 so that the atmospheric pressure chamber 9 is in free communication with the atmosphere at all times.

At its reduced gas receiving end 4 the body portion 2 is formed with a central longitudinal bore 24 (Fig. 5) having an internally threaded portion 25 and a reduced portion 26, the latter portion extending inwardly through the end wall 13 of chamber 11 and slidably receiving a valve stem 27, the inner end of the valve stem projecting into the channel 11 and being provided with a longitudinal slot 28.

The valve stem is formed adjacent its outer end with a reduced portion 30 which extends outwardly through a central bore 32 provided in the guide sleeve 33, the guide sleeve being accommodated within the threaded portion 25 of the bore and having a reduced portion 34 extending inwardly into the reduced portion 26 of the bore. The annular shoulder 35 of the guide sleeve cooperates with the annular shoulder 36 of the bore formed by the reduced portion 26 to limit the inward movement of the guide sleeve. Preferably, a rubber washer 37 is interposed between the annular shoulders 35 and 36.

A spacer ring 38 is disposed in the threaded portion 25 of the bore outwardly of and abutting the guide sleeve 33 and is formed with a central opening 39. Adjacent the periphery of said opening 39 the ring is formed with an outwardly directed spacer flange 40 adapted to abut the inner face of a holding ring 43 and to form a gas inlet chamber 41 between the spacer and holding rings, the

outwardly directed flange 40 being formed with radial slots 42.

The spacer ring 38 and guide sleeve 33 are held in position against outward movement by the holding ring 43 which has external threads which cooperate with the internal threads of the portion 25 of the bore. The holding ring 43 is provided with a central opening 44 which accommodates a nozzle 45 projecting inwardly from the coupling 46 having a reduced externally threaded portion 47 which is screwed into the outer end of the internally threaded portion 25 of the bore 24, the shoulder 48 formed by the reduced portion 47 cooperating with the gas receiving end 4 of the body portion 2 of the housing to limit the inward movement of the coupling. The nozzle 45 is provided with a central bore 49 having a reduced portion at its inner end constituting a gas inlet port 51 and the inner end of the nozzle is formed with an annular recess 52 about the reduced portion to receive a rubber ring, the ring constituting a valve seat 53. The outer end of the valve stem is formed with a further reduced portion constituting a needle valve 54.

The diaphragm is operatively connected to the valve in the following manner. Discs 55 of suitable material such as aluminum are provided on both sides of the diaphragm adjacent its central portion and are secured to the diaphragm by suitable means here shown as a screw 56 passing through the center of the discs and diaphragm into a threaded recess in a stud 57. The inner end of the stud extends inwardly into the channel 11 and is provided with a slot 58 for pivotally receiving the end of one arm 59 of a bell crank 60. The arm extends thence within the channel 11 toward the channel end wall 13 adjacent to which it is pivotally mounted between a pair of spaced ears 61 which project inwardly into the channel. The other arm 62 of the bell crank is formed with spaced fingers 63 and 64 which are received in the longitudinal slot 28 of the inner end of the valve stem 27 and straddle a pin 65 passing through said slot.

When the diaphragm is in its normal position, as shown in Fig. 5, with both faces of the diaphragm exposed to atmospheric pressure, the parts are so arranged that the needle valve 54 is in seated position on the valve seat 53, thereby closing the gas inlet port 51. Depression of the diaphragm inwardly of the control chamber 10 causes the bell crank arms to pivot thereby to retract the valve and to cause it to become unseated and to open the gas inlet port. The return of the diaphragm to said normal position causes the parts to move in the opposite direction to advance the valve 54 to seated position thereby to close the gas inlet port 51.

At one side of the channel 11, the body portion 3 of the housing is provided with an atmospheric pressure gas inlet port 67 (Fig. 4) providing communication between the atmosphere and the control chamber 10, the inflow of air being controlled by a suitable valve 68 here shown for example as comprising a cylindrical casing 69 having a central bore 70 provided adjacent its outer end with a reduced portion 71 forming an annular shoulder 72 constituting a valve seat. A disc 73 constituting a valve is disposed in seated position upon the shoulder and is resiliently urged outwardly to seated position by means of a helical spring 74 having its outer end in contact with the inner face of the disc and its inner end fast to the bases 75 of a pair of crossed wire bails, the legs 76 of the bails being frictionally received at their ends into recesses provided in the shoulder. The inner end of the cylindrical casing 69 is secured to the outer face of the body portion 3 of the housing over the atmospheric pressure gas inlet port 67 by suitable means as screws 77 (Fig. 1) passing through openings in ears 78 projecting laterally from the casing at its inner end, the screws being threadedly received by openings in the body portion 3 of the housing. Instead of communicating with the atmosphere the valve 68 may

communicate with the interior of a rubber bag (not shown) supplied with oxygen or any mixture of life supporting gases at atmospheric pressure. With such an arrangement the gas within the bag should be maintained at atmospheric pressure.

At the opposite side of the channel 11, the body portion 3 of the housing is provided with a gas outlet port 79 providing communication between the atmosphere and the interior of the control chamber 10, the outflow of gas being controlled by a valve 80 here shown as of the same construction as valve 68 except that the reduced portion of the bore is at the inner end of the cylindrical casing and the disc 73 is resiliently urged inwardly to seated position by the helical spring 74. The spring 74 is seated on the crossed wire member 75.

Below the floor 12 of the channel 11, a central longitudinal bore 82 (Fig. 5) extends in reduced steps through the body portion 2 from the delivery end 5 respectively to form the portion 83 and reduced portions 84, 85 and 86. From the inner end of reduced portion 86 a passage 87 extends inwardly and obliquely to communicate with the portion 25 of the longitudinal bore 24 and thence through notches 37a, 33a and 38a provided respectively in the peripheral margin of rubber washer 37, guide sleeve 33 and spacer ring 38 into communication with the gas inlet chamber 41, the notches 37a, 33a and 38a constituting a gas outlet port.

An elongate cylindrical casing 90 having an annular flange 91 at its outer end is disposed within the longitudinal bore 82, the casing 90 being disposed within the reduced portion 85 and the flange 91 within the reduced portion 84, the shoulder 92 formed by the flange cooperating with the shoulder 93 formed by the reduced portion 85 to limit the inward movement of the casing. Within its inner end the casing 90 is formed with a nozzle tube 94 (Fig. 5) the inner or exit end of the tube being shaped to constitute the primary nozzle of an aspirator device having an orifice 95 of restricted cross section so that the speed of gas passing through the orifice is accelerated, the passage 87, reduced portion 86 and nozzle tube 94 constituting a conduit. The orifice 95 delivers the gas into the interior of a secondary or force nozzle 96 within the casing which has an orifice 97 of larger cross section than that of the orifice 95. A port 98 affords communication between the interior of the nozzle 96 and a suction chamber 99 within the casing into which the gas is delivered through orifice 97. At the mixing chamber the casing is provided with a passage 100 which communicates with a passage 101 in the floor 12 of the channel 11 thereby affording communication between the mixing chamber and the control chamber 10. The port 98 is of slightly larger cross section than that of the orifice 97. As the gas emerges from the orifice 95 it induces a flow of gas from the suction chamber 99 in through the port 98 and into the nozzle 96.

An exit throat or passage 102 leads from the suction chamber 99, being coaxial with orifice 97 and thence diverges outwardly within the casing into communication with a central longitudinal bore 103 of a cylindrical spacer casing 104 disposed within the reduced portion 84 of the bore 82. The passage 102 constitutes a venturi wherein the gas delivered from the orifice 97 into the mixing chamber passes through the passage 102 where it is allowed to expand thereby to create a reduced pressure within the mixing chamber causing a suction through the passages 100 and 101 to draw gas from the control chamber 10.

The inner end of the spacer casing 104 abuts the outer end of the cylindrical casing 90 and the outer end of the spacer casing is externally threaded and is adapted to cooperate with the internal threads 105 provided in the reduced portion 84 to hold the cylindrical casing 90 in position within the reduced portion 85. The passage 83 in the base 82 is also internally threaded to receive an externally threaded portion of the coupling 106 of a

delivery hose 107 (Fig. 6), the passage 102, bore 103 and passage 83 constituting a delivery chamber. While not essential, a passage 108 is preferably provided between the inner end of the passage 83 and the floor 12 of the channel 11, thereby to provide a further communication between the interior of the control chamber 10 and the delivery chamber.

Adjacent to the gas receiving end 4, the elongate body portion 2 of the housing is provided with a threaded passage 110 providing communication between the atmosphere and the passage 87. The passage 110 is normally closed by suitable means as a threaded plug 110a except when the valve is employed with an auxiliary device, as for example an aspirator, as will hereinafter be described.

One use of the breathing assist valve of the present invention is illustrated in Fig. 6 wherein the valve is shown connected between a source of compressed oxygen within the tank 120 and a face mask 121 of well known construction adapted to fit over the mouth and nose of a patient. Intermediate the tank 120 and coupling 46 at the gas receiving end of the valve standard commercial equipment is provided including couplings 200 and 122, a gauge 123 for indicating the amount of gas within the tank, a gauge 124 for indicating the pressure at which gas is being delivered to the valve, a pressure regulator 125 for controlling the pressure of the gas being delivered to the valve, and couplings 126 and 127. Intermediate the coupling 105 of the delivery hose 107 and the face mask 121 a gauge 128 is provided which indicates the pressure in centimeters of water at which gas is being delivered from the valve to the face mask. In one embodiment, as shown in Fig. 4a, when it is desired to prevent exhaled gases from reaching the chamber 10, a second atmospheric pressure inlet valve identical to the valve 68 is substituted for the exhalation valve 80 and an exhalation valve 129 (Fig. 6) is provided at the face mask. The valve 129 has a passage (not shown) which communicates with the atmosphere during exhalation and which is closed during inhalation so that exhaled air passes to the atmosphere and does not enter the tube 107.

With the face mask in position over the patient's mouth and nose, gas being supplied to the gas receiving end 4 of the valve and the parts of the valve in normal closed position shown in Fig. 5, both faces of the diaphragm being exposed to atmospheric pressure and the valve 54 is in seated position closing the gas inlet 51, the initiation of inhalation by the patient creates a slight negative pressure within the mask. This negative pressure is transmitted through the hose 107 into the delivery chamber 82, thence directly through passage 108, or indirectly through the bore 103, passage 102, the suction chamber 99, passages 100 and 101 to the control chamber 10 where it acts upon the inner face of the diaphragm 8 to move it inwardly of the chamber 10. This movement causes the bell crank 60 to retract the needle valve 54 from seated position and thus to slightly open the gas inlet port 51. The gas under pressure then flows from the tank 120 to the gas inlet chamber 41 through the radial slots 42, thence through the gas outlet port comprising the notches 37a, 33a and 38a, thence through the passage 87, reduced portion 86, nozzle tube 94, orifice 95, forcer nozzle 96 and orifice 97 into the suction chamber 99 and thence through the venturi passage 102.

As the gas passes through the venturi passage 102 the suction thus created withdraws gas (air in the embodiment illustrated) from the control chamber 10 through the passages 101 and 100 and thus further reduces the pressure within the valve chamber 10 and further depresses the diaphragm which causes the needle valve 54 to be further retracted and the gas inlet port 51 to be opened further as shown in dot and dash lines in Fig. 5. The volume of gas thus increased by the increased supply of gas from the tank 20 and the increased supply of gas from the chamber 10 flows under pressure from the

delivery chamber through the hose 107 to the face mask to assist the patient during the completion of his period of inhalation without further effort on the patient's part.

During this operation the increase in negative pressure

5 within the control chamber 10 overcomes the resistance of the spring 74 in the valve 68 controlling the atmospheric pressure inlet port 67, and the inlet valve 68 is opened to provide a supply of air (or other life sustaining gas) to the control chamber 10.

10 Upon the termination of the patient's period of inhalation, the patient's lungs resist the further delivery of gas, and this resistance causes the negative pressure in the chamber 10 to be restored to atmospheric pressure and such atmospheric pressure causes the spring 74 to close

15 the atmospheric pressure valve 73 and causes the diaphragm to return to its normal position (shown in Fig. 5). This action advances the needle valve 54 to its seated position (shown in full in Fig. 5) and closes the gas inlet port 51 to shut off the supply of gas from the tank 120.

20 The exhalation opens the exhalation valve 129 (Fig. 6) to permit the normal exhalation of the patient therethrough to the atmosphere. At the next initiation of inhalation by the patient, the cycle above described is again repeated.

25 The above described operation includes use of the exhalation valve 129 and two atmospheric pressure inlet valves 68. When a patient is free of contagious diseases which would contaminate the breathing assist valve of the invention, the exhalation valve 129 may be eliminated

30 and the exhalation valve 80 may be substituted for one of the inlet valves 68 as shown in Fig. 4. In this embodiment the patient exhales through the hose 107, the passage 108 or passages 100 and 101 into the control chamber 10, and thence to the atmosphere through the

35 outlet port 79, the positive pressure overcoming the resistance of the spring 74 to open the valve 73.

When the valve is used with the diaphragm 8 in a substantially horizontal position and the chamber 9 below the diaphragm, gravity returns the diaphragm to the normal position shown in Fig. 5 after each period of inhalation. When the diaphragm 8 is in a vertical position during use (as shown in Figs. 6 and 9) means should be provided to insure such return of the diaphragm. Suitable means for accomplishing this result

45 are here shown, by way of example, as forming the cover 6 with the outwardly extending, substantially cylindrical shaped casing 135 (Figs. 4 and 5) having a partially threaded central bore 136 in communication with the outer air pressure chamber 9. The bore 136 accommodates an externally threaded annular ring 137 which is adjustable throughout the threaded length of the bore. The outer face of the ring is provided with radially extending recesses 138 which receive and hold opposite ends of a bar 139 extending across a central opening 140 provided in the ring. A helical spring 141 is disposed within the bore inwardly of the ring, one end 142 of the spring extending through the ring opening and being connected to the bar 138. The other end 143 of the spring extends inwardly into the outer air pressure chamber where it is secured to a freely rotating wire or loop 144 connected to the head of screw 56. By adjusting the ring 137 within the bore the spring 141 is tensioned so as to very delicately urge the diaphragm to the normal position shown in Fig. 5. The outer end of the bore is provided with a threaded cap 145 to keep any foreign matter from entering the outer air pressure chamber 9.

55 In Figs. 7 and 8, the breathing assist valve of the invention is shown in use with a face mask and an auxiliary device connected to the mask and here shown as an atomizer 150 for administering medicine. The atomizer is of the type described in detail in United States Patent No. 2,535,844 and comprises a casing 151 defining a chamber 152 the lower part of which constitutes a reservoir for a supply of the medicine or other

70 75

substance to be administered. The casing 151 is provided with a tubular branch 153 defining a delivery passage 154 and the outer end of the branch is frictionally received in a perforation in the face mask 121. Within the chamber 152 a jet nozzle 155 is supplied with medicine or other substance by means of an elevating tube 156 supported by the bracket 157, the upper end of the elevating tube being so arranged relative to the jet nozzle 155 that the gas delivered from the jet nozzle 155 lifts the medicinal substance to the tip of the nozzle on the tube 156 and atomizes it within the chamber 151. The nozzle 155 is supplied with gas under pressure by means of a flexible tube 158 connected at one end to the outer extension 159 and connected at the opposite end to a coupling 160 which is threadedly received into the threaded passage 110 in the elongate body portion 2 of the housing in lieu of the threaded plug 110a (Fig. 5).

In operation, the breathing assistor valve operates in exactly the same manner as above described in connection with the use of the face mask, the only difference being that simultaneously with the inhalation period and only during that period, a portion of the gas flowing under pressure through the passage 87 while the gas inlet port is open flows through the passage 110, tube 158 into the jet nozzle 155, thereby to atomize the medicinal substance and to deliver it through the delivery passage 154 into the face mask where it is mixed with the gas entering the mask through the tube 107 and is then transmitted to the patient's lungs during the period of inhalation. At the termination of the inhalation the gas inlet port 51 is closed as above described, thereby shutting off the supply of gas under pressure to the jet nozzle 155 and terminating atomization the next period of inhalation.

Fig. 9 shows the breathing assistor valve of the present invention associated with a device for administering anesthesia. A standard commercial anesthesia bag 170 is encased in an air-tight chamber 171 defined by a transparent casing 172, the bag and casing being supported by a tube 173 depending from the member 174 upon which is mounted the controls 175 customarily used in connection with the administration of anesthesia. Oxygen and anesthesia gas are supplied to the anesthesia bag through the tube 173 and the patient breathes directly into and from the anesthesia bag in accordance with established anesthesia administering methods. The delivery hose 107 is connected to a nipple 176 projecting from the casing 172 and having a passage in communication with the interior of the chamber 171. Insofar as the parts shown in Fig. 9 are the same as those shown in Fig. 1, they have been given the same reference numerals.

In use, as the patient initiates inhalation from the anesthesia bag 170 the bag starts to deflate thereby reducing the pressure surrounding the bag within the chamber 171 to create a slight negative pressure therein. This negative pressure is transmitted through the hose 107 into the delivery chamber of the breathing assistor valve in the same manner above described in connection with the use of the face mask, thereby to set off the same cycle and to result in the delivery of a volume of mixed gases through the hose 107 into the chamber 171 to force the bag further to deflate, thereby artificially assisting the patient to complete a period of inhalation without any further effort on his part. Upon termination of the period of inhalation the patient's lungs resist further expansion and this creates positive pressure within the anesthesia bag equalizing and resisting the delivery pressure of the gas surrounding the bag, thereby causing the closing of the gas inlet port 51 of the assistor valve in the manner already described in connection with the operation of the valve with a face mask. As the patient exhales the bag is inflated and the positive pressure thereby caused in the chamber 171 is returned through the hose 107 to the control chamber 10 where it is released through the outlet valve 73 in the same manner as de-

scribed in the case where a patient exhales directly into the berathing assistor valve.

The tank 120 is normally filled with oxygen.

In use, the operator observes the indicator 128 and adjusts the pressure transmitted through the tube 107 by manipulating the control 125 for the pressure regulator. This is to adjust the amount of assisting pressure used and thereby to prevent the building up of excessive pressures in the patient's lungs.

It should be understood that the present disclosure is for the purpose of illustration only and that this invention includes all modifications and equivalents which fall within the scope of the appended claims.

I claim:

- 15 1. A breathing assistor valve for providing positive pressure substantially throughout each period of inhalation of a user comprising a delivery chamber having a delivery port, means for operably connecting said delivery port with an airway to the user's lungs, a positive pressure gas inlet port adapted to provide communication with a source of gas under positive pressure, a closure member for said positive pressure gas inlet port, a conduit providing communication between the positive pressure gas inlet port and the delivery chamber, said conduit being defined in part by a suction chamber which is in continuous communication with said delivery chamber, a control chamber having a suction chamber passage continuously providing communication between the control chamber and the suction chamber, an atmospheric pressure gas inlet port for providing communication between the suction chamber and a source of gas under atmospheric pressure, a check valve for said atmospheric pressure gas inlet port adapted to open in response to reduced pressure of a predetermined amount in the control chamber, said conduit being also defined in part by means for aspirating gas out of said control chamber through said suction chamber passage and into said suction chamber in response to the flow of gas from said source of gas under positive pressure through said gas inlet port and said conduit and consequently through said aspirating means and suction chamber, said aspirating means being defined in part by said suction chamber, means for normally urging said closure member into a substantially closed position, means, responsive to the negative pressure transmitted through said delivery chamber, suction chamber and suction chamber passage to said control chamber upon the initiation of each inhalation by the user, to open said closure member and initiate a substantial flow of gas through said conduit and aspirating means, said pressure responsive means being also responsive to the negative pressure created in said control chamber by the aspiration of gas therefrom by said aspirating means in response to said initiated flow of gas through said conduit and said aspirating means, to further open said closure member and increase the flow of gas through said conduit and the pressure in said delivery chamber sufficiently to automatically complete said inhalation with no further effort on the part of the user, said pressure responsive means also being responsive to pressure in said control chamber created by the resistance of the user's lungs to further flow of gas thereto to automatically close said closure member and means effective during at least a part of the time that said closure member is closed for relieving positive pressure in said conduit and delivery chamber, whereby when the closure member for the positive pressure inlet port is opened responsive to negative pressure created in the control chamber through the delivery chamber, suction chamber and suction chamber passage by a slight inspiratory effort of the user gas flows under positive pressure through said conduit and consequently through said aspirating means and said suction chamber and the aspirating action of said aspirating means in response to said flow of said gas therethrough draws gas from the control chamber through said suction chamber passage into the suction chamber further reducing the pressure in the control chamber and further opening the

closure member for the positive pressure gas inlet port, thereby producing positive pressure at said delivery port.

2. A breathing assister valve for providing positive pressure substantially throughout each period of inhalation of a user comprising a delivery chamber having a delivery port, means for operably connecting said delivery port with an airway to the user's lungs, a positive pressure gas inlet port adapted to provide communication with a source of gas under positive pressure, a closure member for said positive pressure gas inlet port, a conduit providing communication between said inlet port and said delivery chamber, said conduit being defined in part by a suction chamber and a port providing continuous communication between said suction chamber and the delivery chamber, a control chamber having a suction chamber passage continuously providing communication between the control chamber and the suction chamber, said control chamber having an atmospheric pressure gas inlet port for providing communication between the control chamber and a source of gas under atmospheric pressure, a check valve for said atmospheric pressure gas inlet port adapted to open in response to reduced pressure of a predetermined amount in the control chamber, said control chamber also having an outlet port, an exhalation check valve for said outlet port adapted to open in response to a predetermined pressure in the control chamber greater than atmospheric pressure, said conduit being also defined in part by means for aspirating gas out of said control chamber through said suction chamber passage and into said suction chamber in response to the flow of gas from said source of gas under positive pressure through said gas inlet port and said conduit and consequently through said aspirating means and suction chamber, said aspirating means being defined in part by said suction chamber, means for normally urging said closure member into a substantially closed position and means, responsive to the negative pressure transmitted through said delivery chamber, suction chamber and suction chamber passage to said control chamber upon the initiation of each inhalation by the user, to open said closure member and initiate a substantial flow of gas through said conduit and aspirating means, said pressure responsive means being also responsive to the negative pressure created in said control chamber by the aspiration of gas therefrom by said aspirating means in response to said initiated flow of gas through said conduit and said aspirating means, to further open said closure member and increase the flow of gas through said conduit and the pressure in said delivery chamber sufficiently to automatically complete said inhalation with no further effort on the part of the user, said pressure responsive means also being responsive to pressure in said control chamber created by the resistance of the user's lungs to further flow of gas thereinto to automatically close said closure member, whereby when the closure member for the positive pressure inlet port is opened responsive to negative pressure created in the control chamber through the delivery chamber, suction chamber and suction chamber passage by a slight inspiratory effort of the user, gas flows under positive pressure through said conduit and consequently through said aspirating means and said suction chamber and the aspirating action of the aspirating means in response to said flow of gas therethrough draws gas from the control chamber through said suction chamber passage into the suction chamber further reducing the pressure in the control chamber and further opening the closure member for the positive pressure gas inlet port, thereby producing positive pressure at said delivery port.

3. The assister valve of claim 1 wherein said pressure responsive control means comprises a flexible diaphragm forming at least a portion of one wall of said control chamber, said diaphragm having the side thereof which is opposite to the control chamber exposed to atmospheric pressure at all times.

4. The assistor valve of claim 1 wherein said conduit includes an aspirating nozzle the discharge end of which is located in the suction chamber and wherein said suction chamber defines the throat of a venturi.

5. A breathing assister valve for providing positive pressure substantially throughout each period of inhalation of a user comprising a delivery chamber having a delivery port, means for operably connecting said delivery port with an airway to the user's lungs, a positive pressure gas inlet port adapted to provide communication with a source of gas under positive pressure, a closure member for said positive pressure gas inlet port, a conduit providing communication between the positive pressure gas inlet port and the delivery chamber, said conduit being defined in part by a suction chamber which is in continuous communication with said delivery chamber, a control chamber having a suction chamber passage continuously providing communication between the control chamber and the suction chamber, said conduit being also defined in part by means for aspirating gas out of said control chamber through said suction chamber passage and into said suction chamber in response to the flow of gas from said source of gas under positive pressure through said gas inlet port and said conduit and consequently through said aspirating means and suction chamber, said aspirating means being defined in part by said suction chamber, means for normally urging said closure member into a substantially closed position, means, responsive to the negative pressure transmitted through said delivery chamber, suction chamber and suction chamber passage to said control chamber upon the initiation of each inhalation by the user, to open said closure member and initiate a substantial flow of gas through said conduit and aspirating means, said pressure responsive means being also responsive to the negative pressure created in said control chamber by the aspiration of gas therefrom by said aspirating means in response to said initiated flow of gas through said conduit and said aspirating means, to further open said closure member and increase the flow of gas through said conduit and the pressure in said delivery chamber sufficiently to automatically complete said inhalation with no further effort on the part of the user, said pressure responsive means also being responsive to pressure in said control chamber created by the resistance of the user's lungs to further flow of gas thereinto to automatically close said closure member, and means effective during at least a part of the time that said closure member is closed to relieve positive pressure in said conduit.
